UNITED STATES PATENT OFFICE.

IRVING H. LYONS AND RAOUL J. GRUENBERG, OF SAN FRANCISCO, CALIFORNIA, AS-
SIGNORS, BY DIRECT AND MESNE ASSIGNMENTS, TO SANFORD F. WALTER, OF SAN
FRANCISCO, CALIFORNIA.

GARMENT RECEPACLE AND HANGER.

1,084,216.

Specification of Letters Patent.

Patented Jan. 13, 1914.

Application filed April 5, 1912. Serial No. 688,650.

To all whom it may concern:

Be it known that we, IRVING H. LYONS and RAOUL J. GRUENBERG, citizens of the United States, residing at San Francisco, in the county of San Francisco and State of California, have invented a new and useful Garment Receptacle and Hanger, of which the following is a specification in such full and clear terms as will enable those skilled 10 in the art to construct and use the same.

This invention relates to a garment receptacle and hanger therefor, the object of which is to supply stores with a suitable receptacle for sending home clothing without 15 unduly wrinkling the same.

It will be understood by those skilled in the art that the ordinary suit case folding box is of such size that it is necessary to fold coats, skirts, shirt waists, etc., several 20 times to get them into the box. This folding necessarily wrinkles the clothing and it is disadvantageous in several ways. With this invention the box is made of such size as to enable all ordinary sized coats to be 25 placed in the box and suspended upon a hanger secured thereto with but a single fold in the garment, this fold being at such a place as to be the least injurious to the appearance thereof.

Another object of the invention is to provide a hanger for the box which will be capable of being folded flat in substantially 30 the same way as the remaining parts of the box.

Another object of the invention is to provide the garment holder with an opening therethrough for the support of a pair of trousers or some other garment as may be desired.

Another object of the invention is to provide a hanger of such size as to prevent the garments placed thereon from being crumpled up in the box if the box is turned 40 up side down or on its side.

Other objects of the invention will appear as the description proceeds.

It will be understood by those skilled in the art that to make a successful box of this character, it should be possible to ship the 50 boxes in a flat condition. Therefore, it is preferable for all of the parts added thereto to conform to this condition in order to be able to ship the boxes without being broken and to ship them at the lowest freight rate,

but where these objects are not a requisite 55 the boxes may be shipped set up.

In the drawings in which the same numeral of reference is applied to the same portion throughout the several views, Figure 1 is a side elevation of one half of 60 a suit box showing the hanger in position therein, Fig. 2 is an edge elevation of the suit box showing the two handles used therewith, Fig. 3 is a front elevation of the box and hanger showing a coat on the hanger 65 and illustrating in dotted lines the position of a pair of trousers within the coat, Fig. 4 is an elevational view of the edge of the box with the coat on the hanger, Fig. 5 is a cross-section on the line 5-5 of Fig. 1, 70 looking in the direction of the arrow, Fig. 6 is a front elevation of a slightly modified form of box and hanger in which the handle forms a part of the hanger, Fig. 7 is a view in section of the edge of the box shown 75 in Fig. 6, Fig. 8 is a view in elevation of the cover used with both preceding forms of the invention, Fig. 9 is a view in section of the cover shown in Fig. 8, Fig. 10 is a view in elevation of a third modified form 80 of the invention in which the handle forms a part of the hanger and in connection with which a cover without a handle may be used, Fig. 11 is an edge view in section of the hanger and box shown in Fig. 10, Fig. 85 12 is a perspective view of the hanger and box shown in Fig. 1 with the hanger turned back to show the manner of attachment to the box, Fig. 13 is a view of the box shown in Fig. 10 when flat, and Fig. 14 is an edge 90 view of the box shown in Fig. 13.

The numeral 1 represents the bottom of the box, which in this instance is made substantially square, or at least large enough in its greatest horizontal dimension to receive 95 a coat upon the hanger 2 without undue folding. This box has the ordinary side members 3, 4, 5, and 6, which side members are secured at the corners by any well known method of fastening, as for example, the 100 corner lock 7. The box and the cover 8 are each provided with a handle 9. This handle is inserted through the slit in the edge of the box or cover as the case may be and it has a portion 10 secured to the side-member and a portion 11 secured to the back-member 1 of the box or cover as the case may be. 105

Depending within the box is a garment hanger 2, which is large enough to adequately support the desired garment and to prevent it from shifting around within the box should the box be turned from one edge to the other edge. This garment hanger is provided with shoulders 2^a, preferably rounded to conform to a garment and has an opening 13 therein for the support of 5 smaller garments and it is secured to the box side-member in any suitable manner. The hanger lies flat against the bottom-member of the box when in the knock-down condition and when folded the tang 14 is creased so that the hanger will depend centrally between the top and bottom walls of 10 the box.

In use the box is made of such size as will conveniently hold a coat without folding 20 across the shoulders, the tail of the coat being folded up once in the bottom of the box. The smaller garments such as trousers or any other pieces may be passed through the opening in the coat hanger and hung thereon 25 with a minimum folding.

It will be apparent that the box and holder may be made in several forms, one modification of which is shown in Figs. 6 and 7. In this form of the invention the 30 box has a slot at 21 and the hanger 17 and handle 20 are made of one piece, a flap 22 being punched out of the part 19 which is secured to the edge of the box. The flap is secured to the side of the box and serves to 35 strengthen the connection therewith of the handle. With this form of box, the cover shown in Fig. 8 is used and the latter forms the adjoining handle for the purpose of carrying the box from place to place.

40 Still another modification of the invention is shown in Figs. 10 and 11. In this form of the invention the box is shown at 24 and the garment hanger at 25, said garment hanger having an opening 26 therethrough, 45 the same as in the other forms. At the upper end this garment holder has a handle 27 formed therein and this handle is passed straight through a slit 28 in the upper edge of the box, two tabs 29 and 30 being cut out 50 of the holder and secured to said box edge. With respect to this form of the invention, it will be observed that the only weight carried by the tabs 29 and 30 is the weight of 55 the box itself, all of the weight of the garment being supported upon the hanger which is directly in line with the handle. With this form of the invention but a single handle is necessary and any plain cover may be used in connection therewith. Another 60 advantage gained with this box is that while adding to it a garment holder, the ability to ship the box flat is not lost, the form thereof being shown in Figs. 13 and 14.

Another advantage of this invention lies 65 in the fact that the garments may be hung

up in the box after their delivery without creasing the same by simply opening the bottom of the box, the folded portion of the garment being allowed to drop down out of the box. The box will thus prevent the upper portion of garments on the hanger from becoming dusty. Should it be desired to use the hanger without the box all that is necessary is to detach the hanger from the box and hang it up by placing it on a hook 75 through the opening 40 shown on each of the hangers. This hanger further prevents carelessness in placing garments in the box since it is possible to place them in the box in only one way.

Having thus described our invention what we claim as new and desire to secure by Letters Patent of the United States, is as follows:

1. A garment receptacle, comprising a 85 box, and a garment hanger having a tongue or projection at one end secured to an intermediate part of one side-member of the box and depending freely therefrom, said tongue having a crease or transverse line of 90 flexure to permit the hanger to be swung outwardly from the box to receive a garment and then swung inwardly into an intermediate position within the box.

2. In a garment package, the combination 95 with a foldable box having an edge-member jointed with the box-side, of a pendulous garment-form having at one end a narrowed extension connected by a bending-joint with said edge-member at a distance from and substantially parallel with the said box-side, the pendulous member being folded down against the edge-member and box-side when the box is unfolded into a flat form, and being spaced away from 100 said edge-member and side-member when the box is folded, thereby forming a garment-receiving space between the box-side and the pendulous member.

3. A garment receptacle, comprising a 110 knock-down or foldable box, and a garment hanger having a substantially rectangular body and a tongue or projection at one end secured to an intermediate part of one side-member of said box, whereby the hanger 115 will occupy an intermediate position when the box is folded and will lie flat against the back member when the box is unfolded.

4. In a garment package, the combination 120 with a foldable box having an edge-member jointed with the box-side, an angle-reinforce comprising plate-form parts connected by a bending-joint, said parts being secured respectively to said edge-member and to said box-side respectively at the joint therebetween, of a pendulous garment-form having 125 at one end a narrowed extension connected to said reinforce by a bending-joint with said edge-member at a distance from and substantially parallel with the said box- 130

side, the pendulous member being folded down against the edge-member and box-side when the box is unfolded into a flat form, and being spaced away from both said 5 edge-member and side-member when the box is folded, thereby forming a garment-receiving space between the box-side and the pendulous member.

5. A garment receptacle, comprising a 10 box, a garment hanger secured to an intermediate part of one side-member of the box and supported therefrom, and having a portion projecting through a slot in said side-member and provided with an opening to 15 form a handle.

6. A combined garment hanger and box- 20 enclosure therefor, which consists of a sheet of cardboard cut to provide a handle portion and garment-supporting shoulder portions, and a box having a slit in one side to pass the handle, and means on the hanger to support the box without allowing the box to rest on the garment which may be supported on the hanger.

25 7. In a package for garments, the combination with a box and a cover therefor, formed with a slot in one of its ends, of a garment hanger formed of sheet material, a handle on said hanger adapted to extend 30 through the slot in the box, and shoulders on said handle to support the box thereon.

8. In a package for garments, the combination of a garment hanger formed of sheet

material with rounded upper corners and a longitudinal slot therein, an upwardly extending portion on said sheet perforated to form a handhold, lateral projections on said upwardly extending portion forming shoulders, and a box like receptacle for the hanger formed with a slot to receive the handle 40 portion thereon and against the underside of the end walls of which the shoulders abut to support the receptacle.

9. In a package for garments, the combination of a garment hanger formed of sheet 45 material with rounded upper corners and a longitudinal slot therein, an upwardly extending portion on said sheet perforated to form a handhold, lateral projections on said upwardly extending portion forming shoulders, a box like receptacle for the hanger formed with a slot to receive the handle portion thereon and against the underside of the end walls of which the shoulders abut to support the receptacle, and means for 50 connecting the handle portion to the box to prevent its removal therefrom.

In testimony whereof we have hereunto set our hands this 30th day of March A. D. 1912, in the presence of the two subscribed 60 witnesses.
